ELECTRODE FOR LUMINESCENT TUBES

Roy R. Wiley and Alfred L. Brandt, Sr., Buffalo,
N. Y., assignors to Flexlume Corporation, Tonawanda, N. Y., a corporation of New York

Application March 5, 1929. Serial No. 344,156

1 Claim. (Cl. 176—126)

This invention relates to improvements in the electrode construction of electroluminescent tubes and has particular reference to the protection of the lead-in wires of electrodes of the type shown in a copending application serially numbered 320,150 wherein the active electrode element is arranged within a body.

In electrode constructions of this type, the lead-in wire usually extends along the axial center of the tube from the exterior thereof through the glass seal of the reentrant stem to the body in which the active element is located. According to the prior practice if the body be spaced from the glass seal, the intervening portion of the lead-in wire is ordinarily exposed to the surrounding gas. On the other hand, if the body be fused to the glass seal, the lead-in wire will be insulated from the surrounding gas. The fusion of the body to the glass seal is, however, ordinarily difficult to accomplish, particularly when the body is composed of pyrex-glass which, as now considered, is more desirable than other suitable substances. With the failure of the parts to fuse properly, the lead-in wire obviously remains exposed to the surrounding gas.

It has been observed that when any metal which is connected in the circuit of the tube is placed in the axial center thereof, it will be subjected to an intensive electrical discharging action unless otherwise protected. Consequently it is necessary to protect the lead-in wire when exposed as above mentioned.

The principal object of the invention is to provide a simple construction which may be more or less roughly made and readily assembled and which, nevertheless, will prevent any discharge action from centering around the lead-in wire.

An embodiment of the invention is illustrated in the accompanying drawing, wherein:

40 Figure 1 is a longitudinal section taken through the center of the tube.

Figure 2 is a section along line 2—2 of Figure 1.

45 Figure 3 is a longitudinal central section of a modified construction.

The electroluminescent tube is sufficiently indicated by a showing of its terminal portion 1 in which the reentrant stem is provided with a glass seal 2 through which the lead-in wire 3 passes. The electrode element 4 to which the lead-in wire is connected may be composed of any suitable material and fashioned in any suitable form. Preferably it is composed of copper of foraminous structure and arranged in the 50 form of a cylinder.

The electrode element 4 is arranged within a chamber provided by a body 5 of glass or other suitable insulating material which may be of any suitable form and supported in any suitable manner. As shown and preferred, the body is 60 made of cylindrical shape having the end through which the lead-in wire passes closed as at 6. The electrode element is preferably, although not necessarily anchored in the body. This may be accomplished by heating the body so as to cause 65 it to flow into and fill the foramina in the electrode, leaving a suitable area of the latter exposed as an active area. The anchorage of the electrode element in this manner considerably decreases the surface otherwise available 70 as an active area but even though this reduction of active surface be carried to an extreme the operation of the tube is not impaired.

The body is axially located within the tube preferably with its closed end in abutting relation to the glass seal. The crevice existing between these abutting parts is ordinarily sufficient to permit access of the gas with a resultant discharging action.

In order to prevent a discharging action from 80 taking place and thereby protect the lead-in wire, a cylindrical sleeve 7 is utilized. This sleeve conforms roughly to and fits somewhat closely over the body and also conforms roughly to, and fits somewhat closely over the reentrant stem 85 of the tube. One end of the sleeve bears against the end of the tube and the opposite end of the sleeve 7 indicated at 7b is cup-shaped, that is to say flared outwardly into contact with the walls of the tube and extended forwardly along 90 the walls thereof. Thus both the stem and the body are telescoped within and in substantial contact with the sleeve 7.

With this arrangement it is evident that two gas paths extend from the exposed lead-in wire 95 to the tube proper, one between the sleeve and the body and the other around the outer surface of the sleeve. While the sleeve is intended to fit accurately on the body and the other parts mentioned, the difficulty of obtaining accurate dimensions in glass work of this type renders this practically impossible. The variations in the dimensions will, therefore, insure the existence of the gas paths mentioned. However, the areas of such paths are greatly restricted for a considerable portion of their length and consequently the resistance of the paths to the current flow is very high. We have found that when the sleeve is roughly made the variations naturally occurring are not sufficient to reduce the resistance to the 110

current of either or both paths to an extent such as will permit a discharging action.

The diameter of that portion of the sleeve which extends between the end 7b and the body is preferably reduced to provide a restricted connecting passage 8 between the electrode and the tube proper. The passage 8 functions to reduce the rate of vaporization of the electrode as pointed out in the copending application noted.

10 In the modified form of construction shown, in Figure 3, the body is slightly spaced from the re-entrant stem while the connecting passage is formed directly on the body instead of on the sleeve 7, the details of construction being the same 15 otherwise. This form of construction as well as the form shown in Figures 1 and 2, has the advantage of facilitating the manufacture of the tube. During such manufacture, after the body has been properly arranged, the electrode construction is completed simply by slipping the

sleeve 7 over the body into position. The sleeve preferably is held in place by reducing the diameter of the tube 1 at the end of the sleeve, as shown.

Having fully described our invention, we claim: 80

An electrode construction for electroluminescent tubes comprising in combination with such a tube, an electrode arranged within said tube, a hollow body within which said electrode is supported, a lead-in wire connected to said electrode and extending through a wall of said body, and a sleeve fitting over said body and having a cup-shaped end extending forwardly of said body in contact with the walls of said tube, the portion of said sleeve extending between said body and said cup-shaped end being of reduced diameter to provide a restricted passage connecting the interior of the body to the tube proper. 85
